United States Patent Office.

ISAAC N. ROSS, OF HOLDEN, MASSACHUSETTS, ASSIGNOR TO
EARLE STOVE COMPANY.

Design No. 3,551, dated June 15, 1869.

DESIGN FOR A STOVE.

The Schedule referred to in these Letters Patent and making part of the same.

To all whom it may concern:

Be it known that I, ISAAC N. Ross, of Holden, in the county of Worcester, and State of Massachusetts, have invented a new Design for the Casting of a Heating-Stove; and I do hereby declare the following to be a full, clear, and exact description of the same, reference being had to the accompanying drawings, in which the figure represents, in perspective, a heating-stove, fashioned in accordance with my design.

This stove is circular in horizontal section, and is provided with interior return-flues, and an exterior stand-pipe, communicating with the flue.

The cap is ornamented with a projecting moulding, or cornice, with embossed tracery above and below, and is surrounded by an open foliated urn.

The fire-pot is surrounded by a easing of cast-iron, formed in two parts, the lowermost of which rests upon the cast-iron base at the level of the grate. The lowermost of said parts is contracted toward the bottom, and is provided with a shallow flange, ornamented with a row of elliptical bosses. The side of the lower part is further ornamented with Gothic tracery and pendants, and, at its top, there is a banded astragal moulding, which connects the "upper" and "lower" parts.

The "upper" part recedes from its base, and has a less diameter at its upper line than the diameter of the base of the "lower" part.

Upon the front of the "upper" part is the fuel-door. On either side of said door are transparent panels, for illuminating - windows. At the top of the "upper" part is a projecting cornice.

The casting for the base of the stove is formed with a cornice, and projection at the rear to receive the exterior stand-pipe, a vertical wall surrounding the ash-pit, and a foot-base, which projects toward the front, as is usual.

The cornice is ornamented with a row of arrow-head devices, while the vertical wall and foot-base are ornamented with Gothic tracery and pendants.

The door which closes the ash-pit is provided with two draught-registers.

The whole stands upon four ornamented feet.

What I claim as my invention, is—

The design for stove-castings herein set forth.

ISAAC N. ROSS.
